CLAIM

The ornamental design for a vehicle key, as shown and described.

DESCRIPTION

FIG. 1 is a top view of the vehicle key of the present invention;

FIG. 2 is a bottom view thereof;

FIG. 3 is a top, left-side perspective view thereof;

FIG. 4 is a bottom, right-side perspective view thereof;
FIG. 5 is a left side view thereof, shown enlarged for ease of illustration;

FIG. 6 is a right side view thereof, shown enlarged for ease of illustration;

FIG. 7 is a rear view thereof, shown enlarged for ease of illustration;

FIG. 8 is a front view thereof, shown enlarged for ease of illustration;

FIG. 9 is a top view of a second embodiment of the vehicle key of the present invention;

FIG. 10 is a bottom view thereof;

FIG. 11 is a top, right-side perspective view thereof;

FIG. 12 is a bottom, right-side perspective view thereof;
FIG. 13 is a left side view thereof, shown enlarged for ease of illustration;

FIG. 14 is a right side view thereof, shown enlarged for ease of illustration;

FIG. 15 is a rear view thereof, shown enlarged for ease of illustration; and,

FIG. 16 is a front view thereof, shown enlarged for ease of illustration.
